UNITED STATES PATENT OFFICE.

PAUL MERTENS, OF NEWARK, NEW JERSEY.

COLLAPSIBLE CORKSCREW.

Application filed March 2, 1926. Serial No. 91,827.

This invention relates in general to corkscrews and more particularly to a corkscrew in which the handle is collapsible both to protect the spiral bit of the device and to reduce the size of the device when it is not in use.

One object of the invention is to provide a novel and improved construction and combination of a corkscrew of the character described which comprises a handle having two sections which swing toward and from each other upon opposite sides of the bit whereby the bit may be disposed between the handle portions and prevented from catching exterior objects, and the device occupy a minimum of space when not in use, the handle portions being adapted to be swung outwardly at angles to the bit for operating the latter in removing a cork or the like.

Another object is to provide in such a device novel and improved means for automatically centering the bit between the handle portions and rigidly hold it with relation to the handle when the corkscrew is being used.

Other objects are to provide a construction whereby a corkscrew can be combined with scissors or the like, so that the same handles serve for operating the scissors and the corkscrew and protect the bit of the corkscrew when the scissors are closed, the construction also permitting use of the scissors without any interference or inconvenience from the bit of the corkscrew; to provide a novel and improved construction and combination of stops upon the corkscrew bit and the handle portions for rigidly centering the bit between the handle portions when the corkscrew is being used; to provide a device of this character which is simple and inexpensive in construction, and to obtain other results and advantages as may be brought out by the following description.

For the purpose of illustrating the principles of the invention I have shown in the accompanying drawings the collapsible corkscrew combined with scissors, but it will be understood that the scissors blades could be eliminated and the handle portions modified and the corkscrew combined with other devices than scissors, without departing from the spirit or scope of the invention.

Referring to said drawings, in which corresponding and like parts are designated throughout the several views by the same reference characters,

Figure 1 is a side elevation of a combined scissors and corkscrew embodying the invention, showing the corkscrew and scissors in closed or collapsed position;

Figure 2 is a side elevation of the device showing the handle portions extended for operating the corkscrew;

Figure 3 is a view similar to Figure 2, showing the reverse side of the device;

Figure 4 is a transverse vertical sectional view, taken on the line 4—4 of Figure 2;

Figure 5 is a detached perspective view of the corkscrew bit and the yoke for connecting it to the handle portions, and

Figure 6 is a fragmentary perspective view of one of the handle portions.

Specifically describing the illustrated embodiment of the invention, the reference characters 1 designate two identically shaped sections pivotally connected intermediate their ends as at 2, each section having one end portion in the form of a handle 3 and the other end in the form of a shearing blade 4, the blades 4 cooperating as scissors and being operated by the corresponding handle portions 3.

The handle portions 3 are adapted to move toward and from each other about the pivot 2 in the same plane, and their adjacent faces are cut away or recessed as at 5 to provide a space for a corkscrew bit 6 which has at one end a U-shaped yoke 7 which receives between its arms the sections 1 and is pivotally mounted upon the pivot 2. The extremities of the arms of the yoke 7 are arcuately curved as at 8 concentrically with the pivot 2, and the sections 1 are each formed with a rib 9 which has one face 10 concentric with the ends 8. The ribs 9 terminate in shoulders 11 adapted to cooperatively engage shoulders 12 at the ends of the arcuate end portions 8 of the yoke when the handle portions 3 are swung away from each other, as illustrated in Figures 2 and 3. While it is necessary that only one shoulder 11 be provided upon each section 1 and one shoulder 12 upon each of the arms of the yoke 7, it is preferable that two of the shoulders 11 and 12 be provided upon each of the sections 1 and arms of the yoke, respectively, as illustrated, since it is thus possible to make the sections 1 substantially identical with each other and to apply the yoke 7 to the sections 1 with either arm of the yoke in contact with either section 1, thereby ensuring a minimum of cost of manufacture.

In the operation of the device, when it is desired to use the corkscrew, the handle portions 3 are swung apart, as shown in Figures 2 and 3, one of the shoulders 11 upon each of the sections 1 engaging one of the shoulders 12 upon one of the arms of the yoke 7 so that the corkscrew bit 6 is automatically centered between the handle portions and rigidly held with respect to the handle portions. The device is used as scissors in the ordinary manner by oscillation of the handle portions 3, and this operation is in no way interfered with or otherwise affected by the presence of the corkscrew bit 6. In fact, the position of the bit 6 between the handle portions prevents accidental contact of the hands of the user or exterior objects with the bit, and when the handle portions are swung together the bit 6 is effectively enclosed, as shown in Figure 1. For limiting movement of the handle portions toward each other, lugs or projections 13 may be formed on the adjacent faces of the handle portions.

The pivot 2 is preferably in the form of a screw and passes through openings in the arms of the yoke and in the sections 1, the screw being threaded into one of the arms of the yoke so that the said yoke serves in the nature of a washer which effectively holds the sections 1 in snug operating engagement with each other as is desirable for effective operation of the shearing blades 4.

It will be obvious that the shearing blades 35 might be wholly omitted and the handle portions 3 modified as desired, the essential feature of the invention being the combination of the corkscrew bit and the handle portions connected thereto so as to be collapsible upon opposite sides of the bit or capable of being swung at an angle to the bit for operating the same.

Having thus described the invention, what I claim is:

45 1. A device of the character described comprising a pair of handle portions pivotally connected to swing toward and from each other, a bit having a U-shaped yoke at one end to receive said pivotally connected ends

of said handle portions between its arms, 50 said yoke being pivotally mounted upon the same pivot as said handle portions to arrange said bit between said handle portions and having the ends of its arms arcuately curved concentrically with said pivot and 55 formed with shoulders at the ends of said curved portions, said handle portions having shoulders to automatically cooperatively engage said shoulders on said yoke as said handle portions are swung apart to center and 60 rigidly hold said bit between said handle portions.

2. A device of the character described comprising a pair of handle portions pivotally connected to swing toward and from each other, a bit having a U-shaped yoke at one end to receive said pivotally connected ends of said handle portions between its arms, said yoke being pivotally mounted upon the same pivot as said handle portions to 70 arrange said bit between said handle portions and having the ends of its arms arcuately curved concentrically with said pivot and formed with shoulders at the ends of said curved portions, said handle portions 75 having transverse ribs formed with arcuate faces concentric with said ends of the arms of said yoke and terminating in shoulders to automatically cooperatively engage said shoulders on said yoke as said handle portions are swung apart to center and rigidly hold said bit between said handle portions.

3. A device of the character described comprising a pair of handle portions pivotally connected to swing toward and from each other, a bit pivotally mounted upon the pivot of said handle portions and arranged between them, said bit having its pivoted end arcuately curved concentrically with said pivot and formed with shoulders at the ends of said curved portion, said handle portions having shoulders to automatically cooperatively engage said shoulders on the bit as said handle portions are swung apart to center and rigidly hold said bit between said 90 handle portions.

PAUL MERTENS.
